UNITED STATES PATENT OFFICE.

NATHAN EDWIN COVEL, OF NEWTONVILLE, MASSACHUSETTS.

SOUNDING TOY.

Application filed May 14, 1926. Serial No. 109,063.

The present invention relates to toys, and more particularly to a toy having at least one element thereof made of some edible material such as a lollipop.

5 A lollipop, sometimes called "an all-day sucker", is a candy confection having a small stick embedded therein to facilitate the repeated insertion of the candy into the mouth. Owing to the ease in which lollipops may be manufactured competition in

10 their sale is severe and consequently it is highly desirable to dress or market the lollipops in some distinctive manner having a strong appeal to children.

15 Most children like to make a noise and consequently an object of the present invention is to produce an inexpensive noise-producing toy, the clapping element of which is a lollipop mounted for removal so that it 20 may be consumed when the child becomes tired of the toy.

To the accomplishment of this object, and such others as may hereinafter appear, the invention comprises certain novel combinations and arrangements of parts and details 25 of construction hereinafter described and then particularly pointed out in the appended claims.

In the accompanying drawings:

30 Figure 1 is a front elevation of the noise-producing toy, showing the lollipop clapper suspended by a ribbon between bell-shaped resonating members or surfaces;

35 Fig. 2 is an end elevation of the toy illustrated in Fig. 1;

Fig. 3 is a view from one end, in perspective, showing the lollipop clapper suspended between the bell-shaped resonating members or surfaces by a rubber band secured to said 40 members;

Fig. 4 is a front elevation of a form of the toy in which only one resonating member is employed showing the lollipop clapper suspended on an integral tang struck from said member; and

45 Fig. 5 is a detail in sectional elevation of the construction illustrated in Fig. 4.

As shown in Figs. 1 and 2 the lollipop clapper comprises a small stick 7 having one 50 end embedded in a candy striker 6. In this form of the toy the stick 7 is attached, intermediate its ends, to a ribbon 8 which passes through an opening in a yoke 9. Outside the yoke 9 the ribbon 8 may be tied into a bow 10 to hold the lollipop clapper in position and to give an attractive appearance to the

toy. The yoke 9 forms a bridge connecting two similar members 11 and 12 each of which is formed to simulate a bell when viewed in front or rear elevation. The yoke 60 9 and members 11 and 12 may be stamped from a sheet of thin metal such as tin. The surfaces 11 and 12 are then bowed laterally to impart a curved, bell-shaped form thereto. The yoke 9 is then bent centrally to form a 65 finger-hold and locate the members 11 and 12 opposite each other and in spaced relation. The stick 7 of the lollipop, attached to the ribbon 8, is then loosely secured by drawing the free ends of the ribbon through an 70 opening in the neck 9 and then tied in the bow 10. This leaves the lollipop suspended, like a clapper, between the surfaces 11 and 12.

75 By grasping the yoke 9 between the fingers and shaking the toy, in the same manner as an ordinary bell is rung, the lollipop will swing back and forth between the enclosing surfaces which will be struck by the candy head 6 and resonate, thus producing 80 the desired noise. When the child becomes tired of the toy the lollipop clapper may be removed by untying the ribbon 8 and consumed by the child in the approved manner.

85 Instead of loosely suspending the lollipop clapper from a ribbon 8 its stick 7 may be suspended from a flexible member, such as a rubber band 13 (Fig. 3) which extends transversely in the space between the surfaces 11 and 12. To this end one of the 90 members 11 or 12 carry side ears 14 and 15, produced preferably in the stamping process, each having an opening 16 therein through which the rubber band 13 is passed and secured. The band 13 yields as the toy is 95 shaken thus animating the lollipop clapper.

100 Or, in another form of the toy, the stick 7 may be loosely suspended from a tang 17 (Figs. 4 and 5) struck from a single resonating member and bent downwardly to form a projecting lug. The tang 17 is provided with a perforation 18 roughly cut to produce a series of peripheral burs 19. The stick 7 is thrust through the opening 18 and the burs 19 grip the wood, hold the stick 7 105 in the tang while yet permitting it to swing freely and thus strike the resonating members.

110 The lower edges of the spaced members 11 and 12 constitute a support for the toy so that it may be exhibited in a show-window or show-case in an upright position.

The exterior faces of the surfaces 11 and 12 may be decorated with pictures attractive to children thus promoting sales of the toy and the lollipops therein or therefor.

- 5 Those skilled in the art will recognize that the constructions described, while preferred, may be modified without departing from the spirit and scope of the invention. Obviously the lollipop clapper may be used 10 with either one or two resonating surfaces and in the simplest form of the invention, shown in Figs. 4 and 5, a single such surface is preferred, the yoke 20 in this form being somewhat longer to provide a secure finger- 15 hold.

The nature and scope of the invention having been indicated, and its preferred embodiments having been specifically described, what is claimed as new, is:—

- 20 1. A noise producing toy comprising a metal blank having two ends formed as bell-shaped surfaces connected by a neck, said neck being bent to form a yoke that holds said ends in spaced relation, a piece of flexible material secured to the yoke and depending between said surfaces, and a lollipop 25

pop comprising a stick and a piece of candy on the stick, said flexible material between said surfaces being attached to said stick.

2. A noise producing toy comprising a 30 metal blank having two bell-shaped members comprising surfaces connected by an integral neck, said neck being bent into yoke form to locate the bell-shaped surfaces in spaced relation, the lower, spaced peripheral edges of said members constituting a support for the toy, and a lollipop clapper 35 flexibly connected to the blank between said members.

3. A noise producing toy comprising a 40 metal blank having two parts forming bell-shaped surfaces connected by an integral neck, said neck being bent into yoke form to locate the bell-shaped surfaces in spaced relation, a ribbon secured to depend from said 45 yoke between said surfaces, and a lollipop clapper held loosely between said surfaces by having said ribbon tied to its stick.

In testimony whereof I affix my signature.

NATHAN EDWIN COVEL.
